UNITED STATES PATENT OFFICE.

MITCHELL L. FYKSE, OF MILWAUKEE, WISCONSIN, ASSIGNOR TO BUCYRUS COMPANY,
OF SOUTH MILWAUKEE, WISCONSIN, A CORPORATION OF WISCONSIN.

SADDLE-BLOCK STRUCTURE FOR POWER SHOVELS.

Application filed February 21, 1923. Serial No. 620,369.

To all whom it may concern:

Be it known that I, MITCHELL L. FYKSE, a citizen of the United States, residing at Milwaukee, in the county of Milwaukee and 5 State of Wisconsin, have invented a certain new and useful Improvement in Saddle-Block Structures for Power Shovels, of which the following is a full, clear, concise, and exact description, reference being had 10 to the accompanying drawings, forming a part of this specification.

This invention relates to power shovels and, more particularly, to saddle block structures constituting a part thereof.

15 Saddle block structures are ordinarily employed to maintain proper working relation between the shipper shaft and the dipper handle in that type of shovels in which the dipper handle is mounted for lengthwise shifting as well as swinging movement relative to the boom. Heretofore these saddle block structures have assumed a substantially U-shaped or loop-like form because of 20 the general belief that the dipper handle must be substantially embraced thereby.

The present invention is predicated upon my discovery that a loop-like form of saddle block structure is wholly unnecessary, particularly, in that type of shovel in which the 25 dipper handle is bifurcated and straddles the boom. In fact, in actual practice, under varied conditions of operation, I have found that shovels equipped with substantially L-shaped saddle block structures have 30 rendered complete satisfaction. This novel form of saddle block not only permits of a more compact assembly but also renders it easier to assemble or dismantle the parts.

Other objects and advantages of the present invention will appear from the following description of an illustrative embodiment thereof.

In the drawings:

Figure 1 is a view in elevation of a portion of a power shovel equipped with a saddle block structure constructed in accordance with the present invention.

Figure 2 is a similar view, on a larger scale, of the saddle block structure of Figure 50 1.

Figure 3 is a sectional view taken substantially on the line 3-3 of Figure 2.

The saddle block structure selected for illustration is shown applied to a shovel of 55 the rope thrusting type, such as described

in the patent to Walter Ferris and S. R. W. M. Bager, No. 1,430,298, issued Sept. 26, 1922. This shovel comprises a boom 10 having a shipper shaft 11 journaled in brackets 12 fixed to the boom. The dipper handle 60 13 is bifurcated so as to form two limbs 13' which straddle the boom, and rest upon rollers 14 carried by the shipper shaft. Each roller is provided with a sleeve 15 fitted over a squared portion 16 of the shipper shaft so as to rotate therewith, and also with a guide flange 17 cooperating with the dipper handle. Gear teeth 18 on each roller mesh with appropriate racks 19 fixed to and extending longitudinally of the dipper 65 handle. The shaft 11 also carries a drum 20 fixed thereto. Rotation of this drum, and consequently the shaft and rollers 14, is effected and controlled from the main frame 21 of the shovel through the hoisting cable 70 22 and thrust controlling cable 23 in the manner described in the patent above mentioned.

In order to maintain proper working relation between the dipper handle and rollers 80 14, a pair of substantially L-shaped saddle block structures are employed, one for each limb 13' of the dipper handle. Each structure comprises a hub 24 journaled upon the sleeve 15 of one of the rollers 14 and carrying an upwardly flaring web-like portion 25 disposed adjacent one side of the corresponding dipper handle limb 13'. The web-like portion 25 together with the reinforcing ribs 26 constitute one leg of the L-shaped structure which in conjunction with the flange 17 85 on the corresponding roller prevents lateral displacement of the dipper handle limb. The other leg of the structure comprises a lateral projection 27 carried by the web-like portion and arranged to overhang the corresponding dipper handle limb. A wear plate 28 interposed between the limb and the projection 27 is secured to the projection by any appropriate means, such as screws 29, a 90 heavy removable center pin 30 being employed to insure against slippage between the wear plate and projection.

In assembling, the rollers 14 are placed upon the shipper shaft, the limbs of the 105 dipper handle positioned thereon, and the saddle block structures placed upon the sleeves 15 of the rollers, with the lateral projections 27 overhanging their respective dipper handle limbs. A washer 31 or other 110

appropriate means is then passed over each end of the shipper shaft to retain the parts in assembled relation, each washer shown being retained by an appropriate pin 32.

5 Thus, it will be noted that the saddle block structures are free to swing about the axis of the shipper shaft with the dipper handle and that the dipper handle is restrained from all but lengthwise shifting 10 with respect to the saddle block structures.

Various changes may be made in the embodiment of the invention hereinabove specifically described, without departing from or sacrificing any of the advantages 15 of the invention as defined in the appended claims.

I claim:

1. In a power shovel the combination of a boom, a bifurcated dipper handle having 20 limbs straddling said boom, a pair of separate saddle block structures, one at each side of said boom overhanging a limb of said dipper handle, a shaft carried by said boom supporting said dipper handle and connecting said saddle block structures to retain them in proper working relation with respect to said dipper handle.

2. In a power shovel the combination of a boom, a bifurcated dipper handle straddling 30 said boom, a shaft on said boom supporting said handle, and a pair of separate saddle block structures on said shaft outside of said handle, each structure disposed at one side of a limb of said handle and overhanging 35 said limb.

3. In a power shovel the combination of a shaft, a flanged roller thereon, a dipper handle resting upon and guided by said

roller, and a saddle block structure on said shaft having a portion overhanging said 40 handle to retain said handle on said roller.

4. In a power shovel the combination of a shaft, a roller thereon having a guide flange at one side thereof, a dipper handle resting on said roller, and a saddle block structure 45 on said shaft at the other side of said roller cooperating with said guide flange to guide said handle.

5. In a power shovel the combination of a boom, a shaft extending transversely thereof, a pair of separate saddle block structures on said shaft at opposite sides of said boom, and a bifurcated dipper handle having 50 limbs respectively disposed between said structures and said boom.

6. In a power shovel the combination of a boom, a shaft extending transversely thereof, rollers on said shaft, a bifurcated dipper handle having limbs resting on said rollers respectively, and a separate saddle block 60 structure at one side of each roller having a portion overhanging one of said limbs.

7. In a power shovel the combination of a boom, a bifurcated dipper handle straddling said boom, a shaft on said boom supporting 65 said dipper handle, a saddle block structure at each end of said shaft, each having a portion overhanging a limb of said handle and each movable along said shaft out of operative relation with respect to said limb, and 70 means for retaining said structures in working position on said shaft.

In witness whereof, I hereunto subscribe my name this 17th day of February, 1923.

MITCHELL L. FYKSE.
